(57) **CLAIM**

The ornamental design for a pitcher as shown and described.

DESCRIPTION

FIG. 1 is a top, rear perspective view of a pitcher showing our new design;
FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the pitcher form no part of the claimed design.
